(57) **CLAIM**

I claim the ornamental design for an adjustable pool light, as shown and described.

DESCRIPTION

FIG. 1 is a front and left side perspective view of an adjustable pool light showing my new design;

FIG. 2 is a right side elevation view thereof, the left side being a mirror image thereof;

FIG. 3 is a top plan view thereof;

FIG. 4 is a bottom plan view thereof;

FIG. 5 is a front elevational view thereof; and,

FIG. 6 is a rear elevational view thereof.

The broken line disclosure represents portions of the light which forms no part of the claimed design.
